LETTER OPENER

Eleanor W. Johnson, Two Harbors, Minn.

Application March 10, 1954, Serial No. 29,450

Term of patent 14 years

(Cl. D74—1)

FIG. 2

FIG. 1

FIG. 3

FIG. 4

Fig. 1 is a rear elevational view of a letter opener showing my new design.

Fig. 2 is a side elevational view thereof.

Fig. 3 is a bottom end view; and

Fig. 4 is a front elevational view thereof.

I claim:

The ornamental design for a letter opener, substantially as shown.
